FEED GRINDING MILL

Douglas L. Graham, Auburn, Ind., assignor to
Mix-Mill, Inc.

Filed Aug. 12, 1974, Ser. No. 496,712

Term of patent 14 years

Int. Cl. D15—03

U.S. Cl. D55—1 B

FIG. 1

FIG. 6

FIG. 2

FIG. 3

FIG. 4

FIG. 5

FIG. 1 is a perspective view of a feed grinding mill embodying the ornamental design of the present invention;
 FIG. 2 is an elevational side view of the feed grinding mill in FIG. 1.

FIG. 3 is an elevational front view of the feed grinding mill in FIG. 1.

FIG. 4 is an elevational right side view of the feed grinding mill in FIG. 1.

FIG. 5 is an elevational back view of the feed grinding mill in FIG. 1.

FIG. 6 is a plan view of the feed grinding mill of FIG. 1.

What is claimed is:
 The ornamental design for a feed grinding mill, substantially as shown and described.
